CARTON HOLDERS

Bernhardt J. Krueger, Oak Park, and George W. Willits, Hinsdale, Ill., assignors to Johnson & Johnson, a corporation of New Jersey

Application July 9, 1951, Serial No. 235,734

3 Claims. (Cl. 248—311)

This invention relates to improvements in Carton Holders and it consists of the matters hereinafter described and more particularly pointed out in the appended claims.

Individual items of utility are often packed in multiples in a carton, from which they are withdrawn, generally one at a time, for use as the occasion demands. In many instances such cartons are used in places which afford no convenient manner of storage or support therefor between periods of use. Under such conditions the cartons are often tucked in out of the way places, sometimes to be forgotten, or where the items become so soiled as to make them unfit for use. As an example, in farm milkhouses, discs for filtering milk are employed and such discs should be kept clean for use. Such discs come a number in a carton, and when the carton is once opened for use it is generally placed upon some ledge or other shelf-like support in the milkhouse where the discs are not always protected from dust and dirt.

One of the objects of the present invention is to provide a holder for a carton of items, which holder is not only of a simple inexpensive construction, but which disposes the carton at a place convenient for use and protects the contents of the carton against dust and dirt between periods of actual use.

Another object of the invention is to provide a holder for a carton adapted to be attached to an upright wall in such a manner that the cover of the holder tends to swing into a position to close the holder, after each use thereof, without the aid of springs or the like, thus providing a closed sanitary enclosure for articles therein.

Also, it is an object of the invention to provide a carton holder which protects the contents normally against contamination and outside contact and which embodies but three parts which, when assembled, permits the ready placing of a filled carton thereinto, in a manner permitting ready access to the items therein and a quick removal of an empty carton therefrom.

Again, it is an object of the invention to provide a carton holder, the three parts of which are formed of thin sheet material, each so constructed as to be stiff and rigid so that the holder will not warp or get out of shape in its use for its intended purpose.

The above mentioned objects of the invention, as well as others, together with the advantages thereof, will more fully appear as the specification proceeds.

In the drawings:

Fig. 1 is a perspective view of a carton holder embodying the preferred form of the invention, when in its closed condition and mounted upon an upright wall.

Fig. 2 is a perspective view of the parts of the holder arranged in the order of their assembly on a scale enlarged over that of Fig. 1.

Fig. 3 is a front to rear vertical sectional view through the holder with its cover in the open position, on a scale enlarged over that and as taken on the line 3—3 of Fig. 1.

Fig. 4 is a side to side vertical sectional view through

the holder, as taken on the line 4—4 of Fig. 1, on a scale enlarged over that of Fig. 3.

Fig. 5 is a fragmentary detail perspective view of one of the rear corners of the holder, which will be more fully referred to later.

In general, the holder which is made from sheet material includes an open top and bottom frame-like body having a front wall, side walls and a back wall, and each of these walls has an inturned flange at the bottom for supporting engagement by bottom marginal parts of the carton enclosed in the holder. Portions of certain of said walls extend rearwardly of the back wall and terminate in inturned flanges arranged at an inclination other than a right angle and these flanges are adapted for attachment to an upright supporting wall so that the holder extends downwardly and outwardly from said upright supporting wall. The holder also includes a cover or lid for the open top of the body, which is pivoted to said portions of said certain of said walls back of the back wall of the body and said lid is provided at the back with a flange. When the lid is swung into its raised position it exposes the top of the carton in the holder for the removal of parts of the contents thereof. In its full open position said flange at the back of the cover engages the back of the body and limits its open position to one forward of the perpendicular so that the cover always tends to swing back into the closed position on the body.

Referring now in detail to that embodiment of the invention illustrated in the drawing, the improved holder comprises but three main parts, which best appear in the order of their assembly in Fig. 2, which parts are a body portion 10, open at the top, the bottom and the back, a wall 11 for closing the open back of the body portion, and a cover or lid 12 for the open top of the holder. These parts are preferably made of sheet metal on the order of 24 gauge steel.

The body portion 10 includes a front wall 13 and rearwardly extending end or side walls 14—14, top marginal portions of which are turned over inwardly and downwardly as a hem 15, thereby providing a finished edge and also materially stiffening the structure. These walls are also provided at the bottom with inturned right angled flanges 13a and 14a.

The top edge of the sides 14—14 is longer than the bottom edge and there is thus formed at the rear of each side a triangular extension 16. Each extension is provided with an inturned supporting wall engaging flange 17 and in each flange are openings 18 for nails or screws, arranged with respect to front wall 13 and the remainder of the container so as to permit easy access by a screw driver or other attaching means. The holder, as a whole, is attached through openings 18 to an upright supporting wall 19 which best appears in Fig. 3. The inner lower ends of the flanges 17 substantially meet the rear ends of the flanges 14a on the associated end or side wall and in each of these walls, in substantially the vertical plane of the rear end of the flanges 14a, are spaced openings 20, the purpose of which will appear later.

The back 11 includes a wall 21 which is substantially like the front wall 13 of the body portion 10. The wall 21 includes an inturned finishing and stiffening hem 22 at the top, an inturned right angled flange 23 at the bottom and inturned right angle flanges 24 at the ends thereof. Each of the flanges 24 has a pair of vertically spaced openings 25 therein arranged to match up with the pair of openings 20 in each end or side wall 14. The back 11 is of the same height as the front wall and is of such a length as to fit within the rear ends of the side walls 14—14. When the back is arranged as aforementioned, its flanges 24 engage the inside of the walls and when the pairs of openings 20—25 are lined up, rivets 26 are employed therein to secure the back 11 to the body portion

10 to coat therewith in providing a rectangular frame-like holder body that is open at the top and at the bottom. At this time the flange 23 coats with the flanges 13a and 14a respectively so as to be engaged by the bottom marginal portions of a carton 27 which best appears in the dot and dash lines in Fig. 3, to prevent wider opening.

The cover 12 includes a panel or body 28 having a downwardly extending hem 28a-28b about the front and the major portion of the sides thereof. When the cover 12 is in its closed position, said hem fits about the outside of the upper outer margin of the front and side walls 13-14 of the body portion 10, as best appears in Fig. 1. The rear end portions of hems 28b are offset inwardly as at 30 to fit inside the wider and deeper upper part of the associated triangular extensions 16 and each part 30 is provided with a hole 31 to match up with a hole 32 in the associated extension 16. At the rear of the cover is a right angled flange 33. In assembling the cover with the body of the holder, before described, the holes 31 are lined up with holes 34 in the extensions 16 and rivets 35 are then passed through the aligned holes. This pivotally attaches the cover to the body of the holder. The cover flange 33 is so proportioned in width that the edge of said flange, when said cover is open, will engage the rear face of the back 11, as best appears in Fig. 3 and will limit the cover to a position, leaning forwardly of a perpendicular plane passing through the axis of the rivet 35.

When the holder is attached to an upright supporting wall 19, as in Fig. 3 it extends at a downward and outward angle therefrom. When the cover is swung into the open position shown in Fig. 3 it stands substantially parallel with the back 11 at an angle leaning forwardly of the perpendicular. Thus the cover tends, when swung into open position by gravity, to close itself, retaining the contents of the holder in sanitary condition.

As before described, the carton is supported in the holder by reason of its engagement upon the flanges 13a, 14a and 23, leaving the major portion of the bottom of the carton within said flanges exposed from below. Thus when it is desired to remove an empty carton 27 from the holder, to be replaced by a new and filled one, an upward push on the exposed bottom portion of the carton will lift the same upwardly and in turn cause the carton to swing the cover into the open position to permit placement of a new carton therein. When the new carton has been placed in the holder the lid swings back to the closed position.

The holder is of a light, strong construction and can be made at low cost. Also the holder protects the carton against damage and prevents the contents of the carton, after it has been opened, from becoming soiled to that extent which makes the contents unfit for use.

We claim:

1. A carton holder for attachment to an upright wall to extend in a downwardly inclined direction from the wall, embodying therein an open top body including front, back and end walls, each end wall including portions extending rearwardly of said back wall and terminating in right angled flanges that extend upwardly and rearwardly from the bottom of said back wall at an angle determining the angle of downward inclination of said holder with respect to said wall small enough so that a

carton placed in said holder will be securely held therein by gravity, means extending inwardly from the bottom edges of at least certain of said walls of the body for supporting engagement by a carton placed in said holder, and a cover member pivoted to said holder and capable of being swung into position to uncover the open top of said body, said angle of inclination being small enough so that said cover member will return by gravity into position to cover completely the open top of said body.

2. A carton holder for attachment to an upright wall and to extend in a downwardly inclined direction from the wall, embodying therein an open top body including front, back and end walls, each end wall including portions extending rearwardly of said back wall and terminating in an upright wall engaging right angle flange that extends upwardly and rearwardly from the bottom of said back wall at an angle determining the angle of downward inclination of said holder with respect to said wall small enough so that a carton placed in said holder will be securely held therein by gravity, each of said right angle flanges being disposed to engage an upright wall substantially perpendicular to said end walls, means extending inwardly from the bottom edges of at least certain of said walls of the body for supporting engagement by a carton placed in said holder, and lid means hingedly connected to said holder operative to uncover the open top of said body, said angle of inclination being small enough so that said cover member will return by gravity into position to cover completely the open top of said body.

3. A carton holder for attachment to an upright wall and to extend in a downwardly inclined direction from the wall, embodying therein a body having an open top, said body including a front and two end walls, each end wall terminating at its rear edge in an upright wall-engaging right angled flange that is disposed at an acute angle to said open top, said angle being such as to cause said holder, when attached to an upright wall, to extend downwardly inclined away therefrom at an angle determining the angle of downward inclination of said holder with respect to said wall such that a carton placed in said holder will be securely held therein by gravity, means extending inwardly from the bottom edges of at least certain of said walls of the body for supporting engagement by a carton placed in said holder, and lid means hingedly connected to said holder operative to uncover the open top of said body, said angle of inclination being small enough so that said cover member will return by gravity into position to cover completely the open top of said body.
